LEWVEAN L. BOLSTEAD, OF OCONOMOWOC, WISCONSIN.

INTERMITTENT FEED FOR MACHINES.

Application filed November 23, 1922. Serial No. 602,836.

To all whom it may concern:

Be it known that I, LEWVEAN L. BOLSTEAD, a citizen of the United States, and resident of Oconomowoc, in the county of 5 Waukesha and State of Wisconsin, have invented certain new and useful Improvements in Intermittent Feed for Machines; and I do hereby declare that the following is a full, clear, and exact description 10 thereof.

This invention relates to a mechanism for producing intermittent motion and to a machine which includes such mechanism.

Objects of this invention are to provide 15 a mechanism in which continuous rotary motion is transformed into intermittent rotary motion, in which a gradual speeding up and a gradual slowing down of the intermittently moved part is secured at the start 20 and finish, respectively, of each of its movements, in which a dwell or pause of predetermined length is secured, and in which the intermittently moved part is positively locked during the dwell.

25 Further objects are to provide a machine for individually feeding articles in an intermittent manner, in which a dwell is given each article at one point in its feeding motion, and in which simplicity of construction 30 is attained.

Further objects are to provide a machine which will operate successively upon a series 35 of articles; which will pick up each article, hold it still, stamp it, and pass it on; and which will perform its several functions with a minimum of jarring or jolting of the article.

An embodiment of the invention is shown in the accompanying drawings, in which:

40 Figure 1 is a side elevation of the machine.

Figure 2 is a plan view of the structure shown in Figure 1.

45 Figure 3 is a sectional elevation taken on the line 3-3 of Figure 2.

Figure 4 is a detail of the locking mechanism.

50 Figure 5 is a fragmentary view of the actuating crank arm, roller, and one of the slots of the intermittently moved member.

Figure 6 is a sectional view on the line 6-6 of Figure 4.

55 Referring more particularly to the drawings, it will be seen that the machine comprises a framework provided with uprights 1 and 2 at the forward and rear ends of

the machine and these uprights are connected by longitudinal bracing members 3 and 4. A convenient construction for this machine is to provide either channel or angle irons for the bracing members and to provide transverse bracing members 5 of angle irons fitted into the corners of the framework as may be seen from Figures 1, 2, and 3 of the drawings. A feedway is 60 provided for the machine and is preferably formed of two opposed members provided with inwardly directed flanges 6, (see Figures 2 and 3). These flanges provide a support for the articles 7 as they are fed 65 through the machine.

It is intended that the articles shall be fed in any desired manner—for example, a gravity feed may be employed to bring the articles up to the rotary intermittently operated member to be hereinafter more fully described.

The machine chosen for illustration is primarily adapted for the stamping of cylindrical cans, such as milk cans, for instance, where it is desirable to give a batch number to the entire lot and either individual numbers or dates to the different cans. However, it is to be understood that the detail description and drawing are to 80 be interpreted as illustrative of any machine of this general type and the invention is to be limited only as defined in the appended claims.

85 A pair of discs 8 are rigidly mounted upon a horizontal shaft 9 mounted transversely of the machine and beneath the feedway. These discs are connected with each other by means of a plurality of bars or rods 10, such rods being spaced apart a distance slightly less than the diameter of the cans 7. The outer end of the shaft 9 is provided with a disc 11 which is rigidly secured thereto. This disc is provided with a plurality of radial slots 12 and with 100 peripheral notches 13, which, in fact, may form a continuation of the slots.

105 It will be seen from Figure 3 that as the shaft 9 rotates in the direction of the arrow, the cans will be lifted into position directly over the center of the shaft 9 and from there will be passed to the other side of the guideway and will be discharged from the machine.

110 A second transverse shaft 14 is mounted within bearings upon the lower longitudinal bracing member 3 of the framework. This

shaft has rigidly secured thereto a relatively large gear 15 which is driven from a smaller pinion 16, such pinion being conveniently carried by a third shaft 17 provided with the driven pulley 18, if desired. The outer end of the shaft 14 is provided with a crank arm 19 which carries an inwardly directed projecting portion which may consist of a roller 20 mounted upon a pin 21 secured to the outer end of the crank arm 19, as may be clearly seen from Figures 4 and 5.

From the construction thus far described, it will be seen that when the shaft 14 is rotated in the direction indicated by the arrow in Figure 1 that the projection on the crank will enter one of the slots 12 and as it rocks downwardly, will slide inwardly of the slot and rotate the disc 11 one slot pitch, or the distance between the successive slots. It is to be noted that the interval during which the disc 11 is being rotated is relatively short and that the crank is operatively coupled with the disc through only a small part of one complete rotation of the crank. It is, also, particularly emphasized that the crank enters and leaves the slots in an angular direction and at the periphery of the disc 11, thereby starting disc 11 at a slow rate and stopping it by again gradually slowing it down. Between these two extreme positions the speed of the disc increases to a maximum and then dies down again as the crank approaches the finish of its working stroke with reference to the disc 11. In this manner a sudden jar to the disc, and consequently to the feeding apparatus, is avoided and therefore the machine may be run at a rapid rate without detrimental results.

In order to hold the disc 11 in a locked position, so as to maintain the slots in their relative positions, a catch 22 is provided and is adapted to seat within the peripheral notches of the disc 11. This catch is fully illustrated in Figures 4 and 6 and is shown in connection with the remaining portion of the machine in Figures 1 and 2. It preferably is provided with outwardly directed flanges 23, (see Figure 6), which seat against the under side of the disc 11. It, also, is provided with a cam face 23' against which the projection of the crank is adapted to strike as the crank rocks into operative position, as may be seen from Figure 4. This catch may be conveniently carried by a curved sheet metal member 24 which, adjacent its lower portion, is loosely held to the frame by means of screws 25. A spring 26 urges the catch outwardly into engaging position.

The stamping mechanism may comprise a stamping member 27, of any desired type, adapted to be inked by a pad 28 and to be operated by the forked arms 29, such arms

being guided by an upwardly projecting pin 30. The stamping device is provided with an apertured bottom plate 31 which may be secured to the longitudinal bracing members 4 of the framework, as may be seen from Figures 1, 2, and 3.

The means for operating the stamping device comprises a lever 32 which may be conveniently provided with parallel arms pivotally mounted at 33 upon the uprights 2 of the machine. The outer or free end of the lever has a flattened or down-turned portion 34 which loosely fits over the pin 30 and may be provided with one or more loose washers 35. A buffer spring 36 is positioned between these washers and the transverse portion of the arms 29.

At a point intermediate the ends of the lever 32 a pair of links 37 are pivotally mounted and extend downwardly upon opposite sides of the machine. Their lower ends are joined by means of a transverse rod 38 whose middle portion is secured to an intermediate point upon a lever 39. This lever 39 is pivotally mounted at 40 upon the uprights 2 and projects outwardly beneath the shaft 14. A cam 41 is rigidly secured upon the shaft 14 and is adapted to depress the outer end of the lever.

The operation of the apparatus is as follows:—The cans 7 are passed by gravity, or other means, along the feedway. As the crank 19 rotates, it releases the catch 22 and enters one of the slots 12, thereby imparting a relatively quick motion to the feeding mechanism and positioning the can directly over the shaft 9 and beneath the plate 31 of the stamping apparatus, as may be seen from Figure 3. The can is allowed to dwell in this position while the crank executes the remainder of its stroke. In the meantime the cam 41 depresses the lever 39 and actuates the stamping device to impress the proper marking upon the can. As the crank enters the next slot it again releases the catch and moves the feeding mechanism one step farther, thereby discharging the can and elevating the second can. The stamping mechanism operates after the crank leaves the slot and this cycle of operation is repeated indefinitely and at a relatively rapid rate.

It will be seen from this disclosure that an extremely simple, practical, and efficient mechanism has been provided for transferring continuous rotary motion into intermittent motion.

It will, also, be seen that a device has been provided which utilizes this step by step feature and individually handles a large number of articles in a very short space of time.

It will be further seen that extreme simplicity is attained in this machine and that there are relatively very few parts and such

parts as are employed are of rugged and substantial design.

I claim:—

1. Mechanism for converting continuous rotary motion into intermittent motion comprising a revolvably mounted crank having a projection adjacent its outer end, a movably mounted member having a plurality of slots adapted to successively receive said projection during a portion of a revolution of said crank, and means, releasable by said projection, for locking said member when said projection is free from engagement with said member.
2. Mechanism for converting continuous rotary motion into intermittent rotary motion comprising a revolvable shaft, a crank mounted thereon and having a projection,

a second revolvble shaft, a disc mounted upon said second shaft and having a plurality of radial slots adapted to successively receive said projection during a portion of a revolution of said crank, said disc having a plurality of peripheral notches, and a movably mounted spring pressed catch adapted to seat in said notches when said projection is free from engagement with said slots, said catch having a cam face adapted to cooperate with said projection to disengage said catch when said projection enters a slot.

In testimony that I claim the foregoing I have hereunto set my hand at Oconomowoc, in the county of Waukesha and State of Wisconsin.

LEWVEAN L. BOLSTEAD.
